UNITED STATES PATENT OFFICE.

JEAN THOMAS LEMAIRE, OF HODIMONT-VERVIERS, BELGIUM, ASSIGNOR TO
A. CREMER-PIRNAY & CIE., OF SAME PLACE.

LAP-FORMING MACHINE.

SPECIFICATION forming part of Letters Patent No. 276,606, dated May 1, 1883.

Application filed August 24, 1882. (Model.) Patented in Belgium November 24, 1879, No. 49,902; in Germany June 10, 1880, No. 11,868; in France June 12, 1880, No. 137,222, and in Austria-Hungary September 24, 1880, No. 21,815.

To all whom it may concern:

Be it known that I, JEAN THOMAS LEMAIRE, a subject of the King of Belgium, and a resident of Hodimont-Verviers, in the Kingdom of Belgium, have invented a new and useful Lap-Forming Machine, (for which I have obtained patent in Belgium, No. 49,902, bearing date November 24, 1879; in France, No. 137,222, bearing date June 12, 1880; in Germany, No. 11,868, bearing date June 10, 1880, and in Austria-Hungary, No. 21,815, bearing date September 24, 1880,) of which the following is a specification, reference being had to the accompanying drawings, wherein—

Figure 1 represents a front view of a machine embodying my invention when the mechanism is in the position shown in Fig. 3. Fig. 2 represents a side view of said machine during the process of laying the fleece upon the cylinder. Fig. 3 represents a side view similar to that shown in Fig. 2, except that in Fig. 3 the view is taken when the fleece lapped on the cylinder has attained the desired thickness and part of the circumference of the cylinder has been opened and the fleece broken through. Fig. 4 represents a transverse vertical section through the machine, showing the arm *t* in the position assumed by it when the traps are closed and just before the engagement of said arm with tappet *m*; and Fig. 5 represents a detail view of the horn *o* on shaft *s*, and proximate devices.

This invention relates to devices for doubling the fleece as it comes from a carding-engine to form a lap or bat, which, when it acquires the necessary thickness, is torn open and passed to a second or finishing carding-engine.

In the accompanying drawings, *a* designates a continuously-rotating cylinder, on which the fleece is wound in successive layers as it comes from the breaker. (Not shown.) The course of the fleece is indicated by arrow *z*, Fig. 3. It passes between a roll, *F*, and cylinder *a*, and is wound repeatedly around said cylinder. When broken, as hereinafter described, the bats thus formed are conveyed by a pair of rolls, *G G*, away from said cylinder. The roll

F, in combination with said rotating cylinder, is used for feeding the fleece from the first or breaker carding-engine to said cylinder; or any other equivalent mechanism may be employed for that purpose. The lower roll *G* is driven through the medium of a belt-pulley, *P*, upon the shaft of which is rigidly secured a gear-wheel, *M*, meshing with and driving a large gear-wheel, *N*, secured upon shaft *a'* of cylinder *a* and rotating the same, said wheel *N* in turn driving a wheel, *O*, the latter wheel engaging the teeth of a gear-wheel upon the shaft of said roll *G*.

A part of the periphery of the cylinder *a* consists of two hinged traps, *y y*, which close toward and nearly against each other, and are provided with intermeshing toothed segments *u u'*. A helical retracting spring, *v*, is attached by one end to one of said traps, and by the other end to the relatively immovable part of the cylinder *a*. This spring operates to draw inward the trap to which it is attached, and this motion is communicated through said segments to the other trap, both traps being thus closed, so as to form a part of the cylinder with no protruding portion. The proximate edges of these traps are provided with series of alternating teeth, which are curved to engage with and tear or break the fleece (which has been lapped on said cylinder in successive layers by the rotation thereof,) when the said traps open outward. The trap to which the spring *v* is not attached is provided with a rigid arm, *t*, which is adapted to engage with an external object as the cylinder *a* rotates from right to left, the effect of such engagement being to open said traps outward and break said fleece. If the external object referred to were permanent, the fleece would be broken at each rotation of the cylinder, and therefore it would never be lapped, and the object of my invention would be defeated. It is therefore essential that said object should be presented to said arm *t* only once in the course of a number of the rotations of said cylinder *a*. This number may be two, or it may be any greater number.

The object which I employ for the accom-

plishment of the end above stated is an anti-friction roll attached to the outer end of a tappet, *m*, which is carried by a rock-shaft, *s*, hung parallel to the driving-shaft *a'*. When said rock-shaft is turned so as to raise said tappet into a vertical position the anti-friction roller on said tappet will be struck by arm *t*, as aforesaid, and carried against a fixed stud, *q*, which prevents said tappet from turning to the left beyond the point of contact therewith. The spring *v* then yields, and the traps *u* and *u'* open until the arm *t* has ridden over and beyond the said tappet. When this tappet *m* is turned down into a horizontal position it is out of the path of said arm *t*. The shaft *s* is provided with a collar, fast thereon, having a horn, *o*, which is arranged to be struck by a stud, *j*, extending inwardly from a gear-wheel, *g*. This wheel turns freely on shaft *a'* with rocking or partly-rotary motions, caused by the positive action of a train of gears and a weight, *i*, acting in opposition thereto. These gears are driven from shaft *a'*, as hereinafter explained. The weight *i* is attached to a cord passing over a pulley turning with wheel *g*. The gears turn wheel *g* from left to right, and the weight turns it from right to left, as shown in Figs. 2 and 3. At each motion of wheel *g* in the former direction the stud *j* strikes the horn *o* (see Figs. 4 and 5) from below, rocking shaft *s* from right to left, so as to raise tappet *m* into the path of rotation of arm *t*. The latter then carries this tappet into the position shown in Fig. 4, and the traps open, as before stated. When the arm *t* rides past tappet *m* the stud *j* rides past horn *o*. A weight, *Z*, on a cord passing over a pulley, *X*, on rock-shaft *s*, then turns the said rock-shaft from left to right, thereby restoring tappet *m* and horn *o* to their first position. A stop-plate, *w*, limits the motion of the shaft *s* from left to right, in order that horn *o* may not pass out of the path of oscillation of stud *j*. This plate is of angular form, one arm of it being attached to the frame of the machine and slotted to allow of adjustment, as shown in Fig. 5. The other arm extends outward, so as to be struck by a cam-bar or lifter, *n*, fast on shaft *s*. As the shaft *s* cannot turn farther from left to right after the lifter *n* is in contact with stop-plate *w*, the machine will be locked unless the stud *j* on wheel *g* can get below the horn *o* before the latter returns to its lowest position. To effect this the weight *i* must be temporarily freed from the opposition of the gears which drive said wheel *g*, inasmuch as the force of the driving-shaft of course overcomes said weight. I therefore contrive an automatic severance or unmeshing of the gearing, as follows: Said gearing consists of a worm, *b*, which is fast on the driving-shaft *a'*, a worm-wheel, *c*, meshing with said worm and fast on an upright shaft, *d'*, a bevel-gear wheel, *e*, splined on the latter shaft near its upper end, another bevel-gear wheel, *d*, on a short shaft turning in a fixed attachment of the frame, and a pin-

ion, *f*, on this latter shaft arranged to gear with wheel *g*, aforesaid.

The splined wheel *e* is raised and lowered on its upright shaft *d'* by means of a shipping-lever, *p*, which is pivoted at its upper end to a stud projecting from the frame and extends downwardly, so that its lower end rests upon lifter *n*. This shipping-lever is provided with an arm which extends backward from its pivot-hub parallel to the body of said lever. Both the body of said lever and said arm enter—one on each side—an annular grooved formed around and in said wheel *e*. When the lifter *n* is turned from right to left its eccentric shape causes the shipper-lever *p* to rock upward on its pivot and move wheel *e* above and out of gear with wheel *d*. This occurs shortly before the shaft *s* is free to return to its normal position. As soon as the train of gearing is thus severed the weight *i* causes the wheel *g* to turn until the horn *j* has passed below the spot to be occupied by horn *o* when the latter returns to its lowest position. This last action occurs shortly afterward. The partial rotation of the wheel *g*, under the influence of weight *i*, is limited by the contact of a stop-pin, *k*, extending inwardly therefrom, with a fixed plate or bar, *l*, attached to the frame and preferably curved, so as to hook against said pin in order to effectually stop the rotary movement of said pin and its wheel from right to left. The position of said stop-pin on the wheel obviously determines the distance that horn *j* must travel before striking horn *o*, and consequently the length of flicee that will be received by cylinder *a* before the traps open to break it. A curvilinear series of perforations, *4*, in the wheel *g* allow said stop-pin to be shifted from one position to another around this wheel to regulate the action of the machine, as above stated.

As the operation of all the parts have been fully described *seriatim*, with the reasons for each construction, combination, and arrangement, it is not necessary to recapitulate it here. The beveled construction of the end of arm *t* facilitates the turning backward of the cylinder when desired if the tappet *m* happens to be in such a position that its anti-friction roller could come into contact with said arm on the cylinder, thus turning backward.

What I claim as my invention, and desire to secure by Letters Patent, is—

1. The cylinder *a*, provided with hinged traps *y* *y* in its circumference, forming part of its convex surface, the arm *t*, attached to one of the traps *y*, and the spiral spring *v*, attached to the other trap *y*, and the segments *u* *u'*, attached to the traps *y* *y* and meshing into each other, in combination with the tappet *m*, cam *o*, catch *j*, wheel *g*, and mechanism for operating the foregoing parts, substantially as and for the purpose described.

2. The combination of the wheel *g*, shaft *s*, pinion *f*, bevel-gear wheels *d* and *e*, and means for operating said bevel-gear wheels, fork-le-

ver *p*, lifter *n*, wheel *h*, with weight *i* and catch *j*, attached to wheel *g*, and cam *o*, arranged to operate in the manner and for the purpose substantially as set forth.

5. A cylinder adapted to receive the fleece of wool and provided with traps which form part of its circumference and are capable of outward movement, in combination with auto-

matic devices which move said traps outward and break the fleece whenever a sufficient amount thereof has been wound on said cylinder, substantially as set forth.

JEAN THOMAS LEMAIRE.
